J. S. Jewett & Francis H. Root of Buffalo N. Y.
Letter Patent No 535 Dated Dec 21st 1852.

The schedule referred to in these Letter Patent and making part of the same

To all whom it may concern:

Be it known. That we, J. S.
Jewett and F. H. Root of Buffalo, in the County of Erie, and State of New York have invented or produced a new and ornamental design for Stove Plates, of which the following is a full, clear, and exact description, reference being had to the accompanying drawing which forms part of this specification.

Dec. 535

The Stove plate A, embellished with the ornamental design forming my invention, is adorned on its border by architectural devices consisting of a fluted column (a) to which b is the base & c the capital: d an entablature surmounted by a cornice, or ovolu and cassetto mouldings which forms an ornamental border, and is continued along the top, one vertical edge, and bottom of the plate. The entablature d is connected by a hollow moulding to the body or face of the plate from which a bold, oblong ogee moulding (e) projects, enclosing a panel, of similar figure, having a border formed by a moulding (f) the cross sectional figure of which is an interior cassetto meeting d at a sharp edge, a rounded continuation or extension of the ogee moulding e. On this panel, and enclosed by the border f, is a fanciful enclosing or scroll and floral device B of the configuration represented in the drawing, and consisting of right and left hand scrolls (g) supporting a tripod or three curved ornaments (h) over which is mounted a corbel (i) that has sprouting upwards from it, and to either side, floral scroll devices bearing fruit (k); there are also further floral devices (l) branching upwards from the extremities of the scrolls g.

Having thus described our ornamental design for Stove Plates, what we claim as new therein, is - the embellished panel of the plate, of the configuration herein represented & described.

In testimony whereof we have hereunto subscribed our names.
